UNITED STATES PATENT OFFICE.

CHARLES N. WATERHOUSE, OF ST. LOUIS, MISSOURI, ASSIGNOR TO BUFFUM TOOL COMPANY, OF ST. LOUIS, MISSOURI, A CORPORATION OF MISSOURI.

PLIERS.

1,175,391.

Specification of Letters Patent. Patented Mar. 14, 1916.

Application filed May 18, 1914. Serial No. 839,338.

To all whom it may concern:

Be it known that I, CHARLES N. WATERHOUSE, a citizen of the United States, residing at the city of St. Louis, State of Missouri, have invented a certain new and useful Improvement in Pliers, of which the following is a full, clear, and exact description, such as will enable others skilled in the art to which it appertains to make and use the same.

This invention relates to pliers, and has for its main object to provide a pair of pliers in which the crossed members comprising the same are pivotally connected together in a novel manner.

Another object is to provide a pair of pliers that is equipped with a screw-driver and a cotter pin puller, and which is so designed that the two parts of same can be disconnected easily, when it is desired to use one or the other of said tools.

Other objects and desirable features of my invention will be hereinafter pointed out.

Figure 1 of the drawings is a side elevational view of a tool constructed in accordance with my invention. Fig. 2 is a similar view showing the two members of the tool arranged in a different position. Fig. 3 is an end view of the tool shown in Fig. 1. Fig. 4 is a cross-sectional view taken on the line 4—4 of Fig. 2. Fig. 5 is an edge view of the tool shown in Fig. 1. Fig. 6 is a side-elevational view of one member of the tool. Fig. 7 is a side-elevational view of the other member of the tool; and Fig. 8 is a perspective view of the pivot pin that connects the two members of the tool together.

Referring to the drawings which illustrate the preferred form of my invention, A and B designate the two parts of the tool, each of said parts consisting of a member that has a curved handle 1 and a jaw portion 2. The handle of the member A is provided at its outer end with a wedge-shaped portion that constitutes a screw-driver blade 3, and the handle of the member B is provided at its outer end with a pointed portion that constitutes a cotter pin puller 4. The members A and B are so designed that when they are crossed the jaw portions 2 of same will lie directly opposite each other, and means are provided for pivotally connecting said members together so that they will constitute a pair of pliers when they are com-

bined, as shown in Fig. 1. In order that the members A and B may be disconnected easily, whenever it is desired to use one or the other of the tools 3 and 4, I have provided the member A with a pivot pin 5 that projects into an elongated slot 6 in the member B, said pin having a head 5^a which is so shaped that it can pass through the slot 6 in the member B, and thus permit said members to be separated only when said members are arranged in a certain position. The portion 5^b of the pivot pin 5 that lies adjacent the head 5^a is substantially oblong shaped in cross section, and the narrowest part of said portion corresponds approximately to the width of the narrowest portion of the slot 6 in the member B. Said slot is provided at its opposite ends with enlarged portion 6^a that correspond approximately to the diameter of the widest part of the portion 5^b, and when said portion lies in one or the other of the enlarged portions of the slot 6, as shown in full lines in Figs. 1 and 2, the head on the pivot pin 5 will lap over the member B, and thus prevent said member from being detached from the member A. If it is desired to increase the width of the space between the jaws 2 on the members A and B, it is only necessary to turn one of said members in such a position with relation to the other that the narrow portion of the slot 6 extends in the same general direction as the greatest diameter of the portion 5^b of the pivot pin 5, and then shift one of said members with relation to the other so as to arrange said portion 5^b in the enlarged portion 6^a at the opposite end of the slot 6. In other words, the members A and B are pivotally connected together by a slip joint connection, but, instead of permanently connecting said members together, I have connected said members together in such a manner that they can be completely detached from each other, thus enabling the selected tool, either the screw-driver or the cotter pin puller, to be used independently of the other tool only. The pivot pin 5 is permanently connected to the member A and the portion of said pin that passes through said member is preferably tapered or substantially frusto-conical-shaped, as indicated at 5^c. A nut 5^d is arranged on a reduced threaded extension 5^e of said pin and acts to draw the tapered portion 5^c into intimate engagement with the tapered walls of the

opening in the member A in which it is inserted. By this construction, the pin 5 is held in an absolutely rigid position on the member A and there is no chance for looseness or play between said pin and member.

The end portions of the jaws 2 of the members A and B are serrated at 7, and said jaws are provided with serrated recesses 8 that conform approximately to the external shape of a round rod or pipe when the members A and B are combined, thus enabling the tool to be used for turning a pipe or rod. Each of the jaws 2 is also provided adjacent its inner end with a straight face 9, and when the members A and B are combined and separated slightly, as shown in full lines in Fig. 1, said straight faces 9 will lie parallel to each other, so that they will bear evenly on opposite sides of the square portion on the valve stem of an acetylene gas tank, thus enabling the tool to be used as a key for turning on or off the valve of the tank, without liability of mashing or cutting the stem of the valve, as usually occurs when an ordinary pair of pliers is used to turn the valve of a gas tank.

In addition to the devices previously mentioned, my improved tool is provided with a wire cutter, which is so designed that the jaws of the tool can be slipped over wire that is to be cut in practically the same manner that shears are used to cut wire. As shown in Figs. 6 and 7, each of the members A and B is provided with a notch 10, located at the inner end of the straight face 9 on said member. When said members are combined and arranged in the manner shown in Fig. 1, the notches 10 align with each other, as shown in Fig. 3, thus permitting a strand of wire to be inserted in same. If the handles 1 of said members are pressed together, after a piece of wire has been inserted in the notches 10 in said members, the adjacent edges of said notches, which are sharp, will shear the wire in two.

A tool of the construction above described comprises all of the devices which an automobile generally uses, in keeping an automobile in repair and in adjustment. It comprises a pair of slip joint pliers whose jaws are so formed that they can be used to turn a square or hexagonal nut, or to turn a rod or pipe; it comprises a screw-driver and a cotter pin puller which can be used independently of each other, owing to the fact that the two members or parts of the tool are detachably connected together; it comprises two opposed straight faces that lie parallel to each other, and which are spaced apart a distance equal to the diameter of the square portion on the valve stem of a gas tank,

thus enabling the tool to be used for turning a gas tank valve and it comprises a wire-cutting device which is so arranged that a strand of wire can be cut easily by holding the tool in practically the same manner that shears are used to cut wire.

Having thus described my invention, what I claim is:

1. A tool of the character described, comprising a pair of crossed members, and a pin secured to one of said members that comprises an irregularly-shaped head and a shank, said shank having oppositely-disposed flattened portions throughout its length, and the member to which the pin is secured being provided with a tapered opening that cooperates with a tapered portion on the shank of the pin, said opening also having oppositely-disposed flat portions that cooperate with the flattened portions on said pin to prevent the same from turning, the other crossed member having a slot intermediate its ends that is large enough to admit of the passage therethrough of the head on the pin, when said slot is in a certain position with respect to said head.

2. A tool of the character described, comprising a pair of crossed members, one of said members having a slot intermediate the ends thereof, said slot having enlarged ends; the other of said members having a perforation that aligns with said slot and whose opposite end walls are tapered longitudinally and curved transversely, and whose side walls are straight and parallel; and a pin that passes through said slot and perforation, said pin having a threaded extension at one end and a head at its opposite end, said head being of substantially the same shape as said slot and being adapted to lie across the top of said slot when the tool is in operative position, the shank of said pin having two straight parallel portions that extend from the head to said threaded extension, the end of said portion adjacent the head being adapted to cooperate with the intermediate reduced portion of said slot, and the opposite end cooperating with the straight side walls of said perforation, said shank also being tapered adjacent said threaded extension for cooperation with the tapered end walls of said perforation; and a nut that cooperates with said extension to prevent displacement of said pin.

In testimony whereof I hereunto affix my signature in the presence of two witnesses, this fourteenth day of May, 1914.

CHARLES N. WATERHOUSE.
